ZDENKO FREUND, OF NEWARK, NEW JERSEY.

DESIGN FOR A BACK FOR HAND-MIRRORS, BRUSHES, OR SIMILAR ARTICLES.

SPECIFICATION forming part of Design No. 36,122, dated October 28, 1902.

Application filed September 16, 1902. Serial No. 123,663. Term of patent 7 years.

To all whom it may concern:

Be it known that I, ZDENKO FREUND, a citizen of the United States, residing at 120 Washington street, Newark, in the county of Essex and State of New Jersey, have invented a new, original, and ornamental Design for the Back of a Hand-Mirror, Brush, or Similar Article; and I do declare the following to be a full, clear, and exact description of the same, reference being had to the accompanying drawing, forming a part thereof.

The accompanying drawing shows the back of a hand-mirror to which my design has been applied in relief.

15 The leading features of my design consist of floral sprays and a flowering vine, arranged as illustrated in the accompanying drawings.

20 The main feature of the ornamentation shown is as follows: a series of floral sprays A A, &c., arranged approximately parallel and adjacent to the edge of the article around the entire circumference or border thereof, with a flowering vine B extending approximately diametrically across any blank space 25 of considerable area, as C, left between two opposite portions of said border.

The contributive and essential features of the design are the flower-blossoms or floral rosettes D D, &c., distributed along and about the floral sprays at their bases or tips or intermediately thereof, the flower-blossoms or floral rosettes E E scattered along the vine B, and leaves F F scattered between and along the sprays and vines.

30 While shown as applied to the back and handle of a hand-mirror, it is evident that it could be similarly applied to articles such as brushes, puff-boxes, &c., and to the back or handles of other toilet articles.

35 Having described my invention, what I claim is—

40 The ornamental design for the back of a hand-mirror, brush, or similar article, substantially as shown and described.

45 In testimony whereof I affix my signature in the presence of two witnesses.

ZDENKO FREUND.
